HINGED TYPE FLUE DAMPER WITH
AUXILIARY CLOSURE

Ernst Loewenheim, London, England

Application June 12, 1945, Serial No. 599,091
In Great Britain June 2, 1944

1 Claim. (Cl. 126—285)

1

This invention relates to dampers of the swiveling type.

Dampers of this type are much affected in their operation as the result of the deposit of flue dust in their vicinity and particularly at the bottom of the flues and on stops, guides and the like provided therein and in association with such dampers.

Thus, flue dust may accumulate against the lower edge of the hinged damper when the damper is enclosed and in consequence oppose or prevent altogether its opening.

In other cases, deposits of flue dust may accumulate when the damper is open and provide resistance to its closing.

Such difficulties do not usually arise in connection with dampers of the sliding type, not only because of their vertical instead of circular movement, but also for the reason that when the aperture between the lower edge of the slide and the flue bottom is very small the velocity of the flue gases passing through the aperture which is in the form of a slit increases greatly thereby sweeping away any flue dust which may have accumulated.

With hinged dampers just before they have reached the closed position or shortly after opening, the gases are free to pass around all edges of the damper, or if the damper is of the louvre formation, around all edges of the damper elements. The result is that in a nearly closed louvre damper the velocity of the gases at the bottom of the flue is hardly greater than at other parts of the damper and the flue dust deposits are not automatically removed.

In dampers of this kind, when there is an accumulation of flue dust, the damper has to remain partly opened until the flue dust has been removed by other means, and if it should be attempted to close the damper by force the dust is merely consolidated. If in the case of a louvre damper all of the pivoted damper elements are operated by the same operating gear, as is usually the case, none of the elements can be brought into the fully closed position if any one of them is prevented from closing.

These difficulties are common with hinged dampers and have increased during recent years as, owing to the fuel shortage, inferior fuels generating more flue dust are burned.

The object of the invention is to provide improvements in connection with hinged dampers which will obviate the difficulties above referred to and thus confer on dampers of the hinged type the same advantages as are possessed by sliding

2

and roller blind dampers of the rigid or flexible type.

The invention consists, broadly, in the provision in association with the damper at a position adjacent to where the accumulation of flue dust would be likely to interfere with the closure of the flue by the hinged damper elements of an auxiliary element adapted to be moved independently of the damper element itself into a position in which it will leave a slit or like space between an edge of the damper element and the adjacent portion of the flue and to be brought into a position in which it will close the slit or like space and thus function as a valve.

15 The auxiliary element may be arranged to be operated by means external to the flue and independently from the damper so that it may be opened and closed while the damper is in its closed position.

20 The result of moving the auxiliary element into its open position while the damper is closed is that the flue gases can only flow through the opening, thereby greatly increasing their velocity. In consequence this part is swept clear of any flue dust accumulation.

25 The auxiliary element may itself be of the hinged type or of the sliding type, or of a flexible type, for instance it may be or resemble a flexible roller blind.

30 Where of the rigid type it may also comprise resilient elements or flexible elements to assist in effecting a seal.

35 The auxiliary element may be applied at the bottom of the flue or in any other position, for instance at the sides of horizontal or vertical flues in order to keep the stops or abutments for the damper element free from accumulations of flue dust.

40 The auxiliary element may be operated by an operating gear operated from outside independently from the damper operating gear. It may alternatively be coupled with the latter in such a way that the auxiliary element is moved into the open position just before and during the closing and before and during the opening of the damper.

45 Where the auxiliary element is of the hinged type it may be secured to a shaft pivotally mounted and having secured to it an operating lever, the element being provided optionally with a resilient pad which will rest against the bottom frame when the damper is closed.

50 Where the auxiliary element is of the sliding type, it may be arranged in guides on the frame with which the damper is associated and secured

to means whereby it may be raised and lowered.

Where the auxiliary element is of the flexible type, it may be secured at its lower extremity to a roller, the upper extremity of the element being fixed.

The roller is provided at one or both ends with an extension to which one end of a tape or like flexible element is secured, the other end being connected with a segment connected to a shaft adapted to be rotated by a central gear, the connection of the tape or band and the flexible auxiliary element to the roller being such that by the rotation of the segment the tape or band is unwound from the roller which is in consequence caused to rotate thereby causing the flexible element to be wound about it.

This construction will enable the flexible material to be moved with a minimum of friction between it and the framework of the damper.

The invention will be described further in detail and by way of example with reference to the accompanying drawings in which:

Figure 1 is a view of a damper and its associated frame positioned in a flue;

Figure 2 is a sectional plan view of the construction in question on a major scale;

Figures 3 and 4 are views in elevation illustrating more clearly the mode of construction and operation of the auxiliary element shown in Figures 1 and 2;

Figure 5 is a view in section of a construction of louvered damper;

Figure 6 is a fragmentary view on an enlarged scale also in section of this construction;

Figure 7 is a view in elevation thereof;

Figure 8 is a fragmentary view in section of a construction of a damper with the auxiliary element in the closed position;

Figure 9 is a corresponding view with the auxiliary element in the open position;

Figure 10 is a fragmentary view in elevation;

Figure 11 is a view in plan, and

Figure 12 is a view in section of a further construction of a damper in accordance with the invention.

Referring to Figures 1-4, 1 is the damper blade secured by arms 2 one of which is shown in Figure 2 and to a shaft 3 arranged in a bearing 4 and its upper end in a bearing 5 for rotation by means of the lever 6 secured to it.

The bearing 5 is provided in a cover plate 7 furnished with a lifting eye 8 in forming part of the frame 9 of the damper.

To this frame there are secured flaps of flexible material 10 associated with guards 11 to which their outer edges are secured at intervals by tapes 12 designed to limit the degree of motion which may be imparted to the flaps under the action of the draught.

This frame is shown in Figure 2 associated with flexible flaps 13 by which a gastight joint is made between it and the channel element 14 secured in the walls 15 of the flue.

In brackets 16 extending from the lower end of the frame there is mounted a spindle 17 secured to the auxiliary member 18 which is in the form of a flap and is furnished with a counterweight 19 adapted to constrain it into the position shown in Figure 4.

On each of the frame members there are provided abutments 20 against which this flap will bear when in the closed position and to the spindle there is connected an arm 21 furnished with a roller 22 adapted to co-operate with a ramp 23 so as to cause the auxiliary member 18 to 75

move from the position shown in Figure 4 to the position shown in Figure 3 when the hinged damper is closed.

In opening the damper as will be appreciated the roller 22 descending the damper will permit the auxiliary member to move into the position shown in Figure 4 under the action of the counterweight 19.

Figure 5 illustrates a damper comprising two members 24 pivoted about the axis of the rods 25.

These members are associated with a frame, the upper element 26 and the lower element 27 of which can be seen from the drawings and with the upper member of the frame there is provided a flap 28 of flexible material, a flap 29 of similar material being secured to the lower of the two damper elements.

On the lower element 27 of the frame there is also provided a flap 30 adapted to co-operate with the lower of the two damper members 24 and to its lower frame member there is connected an auxiliary member 31 furnished with a pad 32 and pivoted on a spindle 33 to which is connected a lever 34 in turn connected with a link 35 oscillated by any suitable means so that motion imparted to the lever in the initial opening of the damper will raise the auxiliary member into the position shown in full lines in Figure 6 thereby allowing gases to pass through the lower frame member through the space 36 provided between it and the base 37 of the flue.

In the case of the construction shown in Figures 8 and 9, the auxiliary member indicated by the reference 38 is arranged so that it may be raised vertically under the action of a rod 39 oscillated by any suitable means.

This member is likewise connected with the frame of the flue and the damper itself is arranged to pivot in a manner similar to the lower damper element in the case of the construction shown in Figures 5-7.

Referring to Figures 10-12, 40 is a channel member arranged in the wall of the flue providing an air duct in which the mechanism for operating the damper element and the auxiliary means is located.

The damper element 41 is secured to a shaft 42 supported in bearings, one of which 43 is shown and provided with a gear wheel or the like 44 by which it may be rotated.

On the side member 45 of the damper frame there is secured a member 46 of flexible material, the member 46 being provided with extensions 47 secured by rivets 48 to the frame.

The lower extremity of this flexible member is connected to a roller 49, the end trunnions 50 of which are connected at each end with a band 51 with a segment 52 mounted upon a shaft 53 to which is secured a lever 54, the outer end of which is secured to a rod 55 oscillated by any suitable means.

By moving this lever about the axis of the shaft 53 the segment may be rotated and such rotational motion will impart rotational motion to the shaft 53, thereby operating to raise and lower the bottom portion of the flexible element 46 or in other words roll the lower portion of this element on or unroll it from the roller in question, thereby in the one case providing an opening 56 through which flue gases may pass.

Adjacent to the lower end of the damper frame there are provided guards 57 which also provide a rest for the roller 49 when it is in its lowered position.

I claim:

In a damper construction located in a conduit, the combination of a hinged main damper element; means operable externally of the conduit for moving said element from a fully open position into a substantially fully closed position in which a restricted opening is left between the lower edge of said element and the base of the conduit; and an auxiliary damper element mounted on said main element and operating means for moving the auxiliary damper element into a position to close said restricted opening, when the main element has been moved into its said substantially closed position, and for moving the auxiliary damper from the position in which it closes the restricted opening, before the main element is moved in the reverse direction.

ERNST LOEWENHEIM.
